UNITED STATES PATENT OFFICE

PETER FLANSBURG, OF MANISTEE, MICHIGAN, ASSIGNOR TO SOLOMON H. GOLDBERG,
OF CHICAGO, ILLINOIS

CRATE

Application filed May 17, 1922, Serial No. 561,561. Renewed March 13, 1929.

This invention relates to improvements in crates and refers more particularly to crates used for shipping perishable products such as fruits, vegetables and berries, or fragile articles.

Among the objects of the invention are to provide a double crate consisting of an inner and outer crate, the inner crate mounted upon flexible springs to absorb jarring and shock to the products during transit; to provide a double crate constructed so that it may be readily shipped in knock-down form; to provide a crate in which the perishable products are at all times thoroughly aerated, and are kept intact due to the shock absorbing qualities of the crate; to provide a crate which is more compact both when loaded or in knock-down form, a crate that is rigid and of rugged construction to withstand the abuse to which it is subjected in transit, and one which is more economical both to the manufacturer and producer than those now in use.

Fig. 1 is a perspective view of the double crate with the small berry boxes removed, to show the relative positioning of the inner and outer crates.

Fig. 2 is a sectional view through the center of the crate showing the small boxes in place.

Fig. 3 is a perspective view of the inner crate or box carrier.

Fig. 4 is a perspective view of the inner crate bottom.

Fig. 5 is a detail of the side wires of the inner crate.

Fig. 6 is a detail of the end spring supports for the inner crate, and Fig. 7 is a detail of the middle spring supports for the inner crate.

Referring to the drawing the outer crate 1 may be constructed of any desired material such as heavy cardboard, fibre board, or any other flexible or semi-rigid material which will withstand the abuse to which the crates are subjected in transit, and have sufficient strength to carry the load of the products with which it is filled.

In the drawing is shown a fibre board carton which is glued and stapled together to form a satisfactory and rigid construction.

This is shipped to the producer in knock-

down form so that it is a flat sheet and takes up a relatively small space in shipment. The sides of the carton or outer crate are perforated as shown at 2 to permit thorough ventilation of the perishable products which it contains. At either end of the bottom of the outer crate are positioned the end spring supports 3 whose outer horizontal legs are slightly spread so that they will firmly grip the sides of the crate and thus be held in position.

In the center of the crate is positioned the middle spring support 4 which is identical in form to the end spring supports, except for the crimped center piece 3^a. On these lower spring supports rests the inner crate which consists of a bottom portion 5 and side wires 6. The bottom is slotted along its lateral edges as shown at 7 and also along the ends so that the bottom may be engaged by the turn back portions 6^a of the side wires which are slid into the slots and grip the bottom of the bottom portion forming upright sides or retaining sides for the smaller boxes which are carried on the inner crate.

These side wires are easily removable from the bottom of the inner crate and are shipped detached from the inner crate bottom. In addition to the slots 7 at each end of the inner crate bottom are slots 8 through which the crimped portion 3^a of the end spring supports protrude. These crimped portions hold the inner crate in position in the outer crate and prevent any appreciable lateral or longitudinal movement.

When the crates are shipped to the producer, the outer box or crate 1 is unfolded and is in a flat position as is the bottom of the inner crate, the wires being detached from the inner crate bottom taking up very little space in shipment. The small boxes 9 which are carried by the inner crate are likewise made of prepared cardboard or fibre board and are likewise unfolded to be shipped in flat form. Thus it is possible to transport a great many more of the knock-down crates than the wooden crates commonly used in the shipping of perishable products.

The springs which carry the inner crate, supply a resiliency to the inner crate which

prevents bruising or crushing of the perishable products, and makes it possible to ship products without loss from bruising and crushing in shipment.

5 I claim as my invention:—

1. In a crate for perishable products, the combination with a ventilated outer container, of an inner ventilated box holding crate comprising a bottom and removable side portions, resilient removable means supported in the bottom of the container for carrying the inner crate, said resilient means being intermediately crimped and adapted to register with slots in the crate to prevent accidental displacement and formed to space the bottom of the outer container slightly away from the crate.
2. In a crate for perishable products, the combination with a ventilated outer container, of an inner box holding frame comprising a bottom and upwardly extending skeleton side portions, removable resilient spring supports supported in the bottom of the outer container for carrying the inner box holding frame having intermediate crimps adapted to register with slots in the bottom of the inner box holding frame to prevent accidental displacement, and formed to space the bottom of the outer container slightly away from the inner frame.

PETER FLANSBURG.
